G. B. CLEVELAND

BOOKCASE

Filed Oct. 22, 1925

FIG. 1.

FIG. 2.

Inventor

George B. Cleveland

UNITED STATES PATENT OFFICE.

GEORGE BOWEN CLEVELAND, OF MOBILE, ALABAMA.

BOOKCASE.

Application filed October 22, 1925. Serial No. 64,265.

This invention relates to book cases and has special reference to a sectional book case provided with swinging doors.

One important object of the invention is to provide an improved form of sectional book case wherein the doors of the several sections are arranged in a novel manner so that they all open and close simultaneously.

A second important object of the invention is to provide novel means for effecting such simultaneous opening and closing of the doors of a sectional book case.

With the above and other objects in view as will be hereinafter apparent, the invention consists in general of certain novel details of construction and combinations of parts hereinafter fully described, illustrated in the accompanying drawings and specifically claimed.

20 In the accompanying drawings like characters of reference indicate like parts in the several views, and:

Figure 1 is a perspective view of a book case constructed in accordance with this invention.

Figure 2 is a vertical cross section through the lower part of a book case.

Figure 3 is a section on the line 3—3 of Figure 2.

30 In carrying out the invention there is provided, in general, a base section 1, intermediate or book shelf sections 2 and 3 of any number desired, and a top section or cover 4.

The base section 1 has the usual back and end walls, the latter having forwardly extending prolongations A at their bottom portions and these end walls are connected by a brace strip G. These end walls are provided with alined bearing openings D 40 which receive the pintles or journals E of a treadle B which extends forwardly between the prolongations A. At the back edge of this treadle is a vertically extending riser C which is securely fixed to the treadle

45 20 that its upper edge tilts forwardly as the front edge of the treadle is depressed. The structure thus forms a wide bell crank lever. Projecting rearwardly from the upper part of the riser C is an eye C¹ to which is connected the forward ends of a pair of coiled

tension springs C² having their rear ends connected to laterally spaced eyes C³ fixed to the back board of the section.

Each of the intermediate or book carrying sections has a body of the usual construction, 55 that is to say, provided with a bottom from which rise the usual back wall and end walls H, and the base, intermediate and top sections are held from slipping, one on the other, when assembled by some suitable 60 means here shown as dowels O. Each intermediate section is provided with a pair of doors J hinged to the body in such manner that the hinges K of one section will be vertically alined with the hinges of the remaining sections. It is to be particularly noted that the free ends of the doors of each section are connected to the free ends of the corresponding doors of the adjacent section by dowels L so that, upon assembling the sections, 65 the doors are connected for simultaneous opening and closing movement.

Connecting the doors of the lowermost section, near their hinges, to the riser are links F which are carried by eyes F¹ fixed 70 to the upper corners of the riser C and by pins F² projecting downwardly from the doors of said lowermost section.

Under these conditions pressure on the pedal will open the bottom doors and these 80 will carry with them all the doors above. The spring C² will naturally close the doors when such pressure is removed.

There has thus been provided a simple and efficient device of the kind described and for 85 the purpose specified.

It is obvious that minor changes may be made in the form and construction of the invention without departing from the material spirit thereof. It is not, therefore, desired to confine the invention to the exact 90 form herein shown and described, but it is desired to include all such as properly come within the scope claimed.

Having thus described the invention, what 95 is claimed as new, is:

In a sectional book case, a base section open at the front, a pedal pivoted at its rear edge within the base section, a riser fixed to and extending upwardly from said 100

rear edge, springs normally holding the pedal in substantially horizontal position and resisting depression of the pedal, book sections arranged one above the other with the lowermost book section resting on the base section, doors hinged to each of the book sections, the doors of each section being

detachably connected to the doors of the adjacent section for simultaneous movement, and links connecting the doors of the lowermost book section with said riser.

In testimony whereof I affix my signature.

GEORGE BOWEN CLEVELAND.
